UNITED STATES PATENT OFFICE.

JOHN GREEN, OF ST. LOUIS, MISSOURI, ASSIGNOR TO EDWIN H. BENNERS,
OF ELIZABETH, NEW JERSEY.

CAR-BOLSTER.

No. 799,830.

Specification of Letters Patent.

Patented Sept. 12, 1905.

Application filed January 29, 1904. Serial No. 191,125.

To all whom it may concern:

Be it known that I, JOHN GREEN, a citizen of the United States, and a resident of the city of St. Louis and State of Missouri, have invented 5 a new and useful Improvement in Car-Bolsters, of which the following is a specification.

My invention relates to car-bolsters, either truck-bolsters or body-bolsters; and its principal objects are to cheapen the cost of manufacture of car-bolsters, to reduce the weight of bolsters of given strength, to provide a bolster that may be made of cast-steel with a greater economy in pattern material and core material, to provide a bolster of such construction that the pattern will be easy to draw from the mold and may be drawn without danger of injuring the mold, to provide a bolster that may be used with transom-trucks, with a resulting economy of both material and 20 space, and other objects hereinafter more fully appearing.

My invention consists in the parts and in the arrangements and combinations of parts hereinafter described and claimed.

25 In the accompanying drawings, forming a part of this specification, and wherein like symbols refer to like parts wherever they occur, Figure 1 is a fragmentary sectional view through a truck and car, showing my improved 30 bolster applied both as a truck-bolster and body-bolster. Fig. 2 is a section on the line 2 2 of Fig. 1, omitting the details of the truck. Fig. 3 is a section on the line 3 3 of Fig. 1. Fig. 4 is a section similar to that of Fig. 2, 35 showing the bolster as used with a transom-truck; and Fig. 5 is a plan view of a truck-bolster.

My improved bolster consists of a wide and comparatively thin top member 1, a narrow 40 and comparatively thick bottom member 2, and substantially ogee-shaped members 3 4, which are externally convex at their upper portions and externally concave at their lower portions, the curves merging either with each other 45 or with a substantially straight portion connecting them. These members have this form throughout the length of the bolster, being modified in proportion only from the wide and deep central portion to the narrower and shallower end portions. The bolster thus has a substantially triangular section. In the case of a 50 truck-bolster the section at the extreme ends is substantially rectangular in order to provide the necessary column-guides 5 6, which are of

the usual form. The top member of the truck-bolster is provided with the usual center plate 7 and side bearings 8 9. From the center of the center plate 7 a king-pin post 10 extends from the top member 1 down to the bottom member 2. The king-pin post has an outer diameter 55 equal to or greater than the width of the bottom member. By this construction the king-pin post serves as a strut to transmit the load to the bottom member and distribute it over the entire width of the latter. The bottom member 60 of the body-bolster is provided with the usual side bearings 11 12 and center bearing 13. At the center it is provided with a king-pin post 14, extending from the top member 1 to the bottom member 2. The king-pin 65 post thus serves as a strut in the body-bolster as well as in the truck-bolster. As the bolster is an integral cast-steel article, the top members and the side members have a plurality of holes 15 produced by the core-supporting 70 members of the mold and through which the core may be removed from the casting.

In combination with the cross-tie trucks, as illustrated in Figs. 1 to 3, the truck-bolster extends below the cross-ties 16 17. The bolster being narrow at the bottom, it may extend between the cross-ties, and thus may be made deeper without raising the center plate. As the metal is more efficient in resisting flexure the farther from the axis it is placed, 85 it follows that less metal is required to produce a bolster of given strength. The same advantage obtains in the use of the truck-bolster in transom-trucks, as illustrated in Fig. 4. The body-bolster also has peculiar 90 advantages when used with transom-trucks. Because of the narrow bottom member there is sufficient room for the lateral movement of the body-bolster between the transoms 18 19. Hence it is unnecessary to raise the center 95 plate and side bearings of the truck-bolster above the transoms, and therefore the car-body may lower, space being saved vertically.

Car-bolsters are subjected to horizontal as well as vertical forces, and they are in substantially the plane of the top member. The bolsters illustrated have improved efficiency in taking care of the horizontal strain, for the side members, externally convex at their upper portion, provide metal at the point where 105 it is most efficient for this purpose.

As the bolster converges from the top member to the bottom member, it necessarily fol-

lows that the pattern thereof will draw easily from the mold and the danger of injuring the mold in drawing the pattern is lessened.

Obviously my improved bolster admits of considerable modification within the scope of my invention, and therefore I do not wish to be limited to the specific construction shown and described.

What I claim as my invention, and desire to secure by Letters Patent, is—

1. An integral car-bolster comprising a top member, a bottom member, and side members connecting the top and bottom members to form a substantially triangular cross-section.
2. An integral car-bolster comprising a wide top member, a narrow bottom member, and side members converging from the sides of said top member down to said bottom member.
3. A car-bolster comprising a top member, a bottom member, and side members connecting said top and bottom members, said side members being externally convex at their upper portions and externally concave at their lower portions.
4. A car-bolster comprising a top member, a bottom member, and substantially ogee-shaped side members connecting said top and bottom members.
5. A car-bolster comprising a top member, a bottom member, downwardly-converging side members connecting said top and bottom members, and a king-pin post extending from said top member to said bottom member and arranged to distribute load over the entire width of said bottom member.
6. A car-bolster comprising a wide top member and side members connected to the sides of said top members and downwardly converging to form a substantially triangular cross-section.
7. The combination of a car-truck, having

separated cross-ties, and a bolster having a wide top member, a narrow bottom member and downwardly-converging side members connecting said top and bottom members, said bolster being narrow enough at its lower edge to enter between said cross-ties. 45

8. The combination of a car-truck, transoms therein, a truck-bolster of substantially triangular cross-section the middle lower portions of said bolster extending between and below the lower flange of said transoms, and a body-bolster of substantially triangular cross-section, the middle lower portions of said bolster extending between and below the tops of 55 said transoms.

9. A cast-metal bolster, comprising a top plate having a center and end bearings thereon, a bottom plate, inclined side webs connecting the top and bottom plates and enlarged 60 ends on the bolster integral with the top and bottom plates and side webs.

10. In a bolster, the combination with a top plate flat throughout the greater portion of its length, a bottom plate inclining or curving upward from its center toward the ends of the top plate, and inclined webs connecting side edges of the top and bottom plates. 65

11. A bolster of one integral casting, comprising a top plate, a bottom plate, inclined 70 side webs connecting them, enlarged ribbed ends on the bolster having recesses in their sides, integral center and end bearings on the top plate, and a hollow post in the center of center bearing and depending therefrom. 75

In testimony whereof I have signed my name to this specification in the presence of two subscribing witnesses.

JOHN GREEN.
